DESIGN FOR A PRINTING MACHINE

Franklin E. Curtis, Willoughby, Ohio, assignor
to Addressograph-Multigraph Corporation,
Cleveland, Ohio, a corporation of Delaware

Application February 27, 1939, Serial No. 83,231

Term of patent 7 years

To all whom it may concern:

Be it known that I, Franklin E. Curtis, a citizen of the United States of America, residing at Willoughby, in the county of Lake and the State of Ohio, have invented a new, original, and ornamental Design for a Printing Machine, of which the following is a specification, reference being had to the accompanying drawing, forming part thereof.

In the drawing, Fig. 1 is a perspective view looking at the front and right hand side of the machine and showing my design; Fig. 2 is a perspective view looking at the rear and left hand side of the machine.

I claim:

The ornamental design for a printing machine, substantially as shown.

FRANKLIN E. CURTIS.
